UNITED STATES PATENT OFFICE.

GEORGE W. CHRISTIANS, OF BROOKLYN, NEW YORK, ASSIGNOR TO THOMAS E. MURRAY,
OF NEW YORK, N. Y.

GAGE FOR OBJECTS OF CIRCULAR CROSS-SECTION.

1,290,910.

Specification of Letters Patent.

Patented Jan. 14, 1919.

Application filed July 15, 1918. Serial No. 244,915.

To all whom it may concern:

Be it known that I, GEORGE W. CHRISTIANS, a citizen of the United States, residing at Brooklyn, in the county of Kings and State 5 of New York, have invented a certain new and useful Improvement in Gages for Objects of Circular Cross-Section, of which the following is a specification.

The invention is a gage for objects of circular cross section, such as for projectiles. In my present application, I show my invention as applied to the gaging of an elongated projectile having convex extremities and provided at one end with guide vanes 10 secured to said end. I may apply it to an elongated projectile not having such vanes, and in that case it serves to determine the accuracy of the projectile cylinder. When the guide vanes are present, the gage serves 15 the further purpose of determining whether the central longitudinal axes of the vanes is in line of prolongation of the central longitudinal axis of the cylindrical projectile.

In the accompanying drawings—

Figure 1 is a side elevation of my gage, showing the cylindrical projectile and attached vanes supported on the plane table, and inclosed by the suspended frame—this being the operating position of the device.

Fig. 2 is a plan view of the same. Fig. 3 is a section on the line 3, 3 of Fig. 1, the edges of the table being broken away. Fig. 4 is an enlarged plan view of one end of the gage frame and projectile therein, showing 35 a portion of said frame and inserted detachable plates in horizontal section.

Similar letters of reference indicate like parts.

A is a plane table, preferably of metal, 40 upon which the projectile B to be gaged is supported. To one end of projectile B are attached the guide vanes C, D, disposed at right angles to one another, and having their common central longitudinal axis in 45 the line of prolongation of the central longitudinal axis of projectile B. E is the gage frame, here a casting in parallelogram form suspended by cords F from a bar G which in turn is attached to a suspension cord H 50 which passes over the fixed pulleys I and carries a counter-weight J. The frame can thus be raised and lowered by the hand of the operator, and it may also, in like man-

ner, be moved transversely across the table A.

The opening in the frame E is to be of such length as that the extremities of the projectile will be tangent to the inner end faces of said frame, or if, as here shown, the guide vanes C, D are present, tangent to 60 one end of the projectile and the outer or unsecured ends of said guide vanes. The inner side faces of the frame opening may be tangent to opposite sides of the circumferential periphery of the projectile, but I prefer to make the width of the frame opening greater than the length of the diameter of the projectile so that there will be clearances between said side faces and said projectile, into which clearances I place detachable plates K, L secured to a rib N on the frame by screw bolts, which plates have their inner faces tangent to the projectile, as shown in the drawings. The object of plates K, L is to insure a more accurate 70 centering of the projectile in the frame, and also more accurate lines of tangency. Between the longitudinal edges of the guide vanes C, D and the frame there may be a narrow clearance M, so that said vanes do 75 not rest upon the table A, but are supported by the projectile, to which, as aforesaid, they are secured.

The operation is as follows:

The frame E is moved downwardly until 85 it incloses the projectile and guide vanes, as shown in Fig. 1, with the plates K, L in contact with the circumferential periphery of said projectile. The frame E is then, by the hands of the operator, moved laterally 90—that is, at right angles to the longitudinal central axis of the projectile—thus causing the projectile to rotate or roll upon the table. If the guide vanes are not present and the projectile completes an entire rotation without binding in the frame, it is so shown to 95 be truly cylindrical. If the guide vanes are present and the projectile completes an entire rotation without binding in the frame, it is so shown, first, that the projectile is 100 truly cylindrical, and, second, that the common central longitudinal axis of the guide vanes is in line of prolongation of the central longitudinal axis of the projectile, with a permitted error depending on the amount of 105 the clearance at M. For if said vanes were

not in said line their common central longitudinal axis would stand at an angle to the central axis of the projectile, and if that angle were beyond that permitted by the clearance aforesaid, then the whole structure 5 (projectile and vanes) would bind in the frame.

The type of vaned projectile here shown is designed for use in trench mortars for 10 projection over short distances, and hence a slight deviation, as above noted, from exact alinement of the axis of the projectile and that of its vanes does not materially affect the accuracy of flight. But if, for any 15 reason, it be desired that there should be exact alinement of said axes, the plates K, L may be extended so that they will be tangent to the longitudinal edges of the vanes as well as to the periphery of the projectile; or 20 if the plates K, L are omitted, the periphery of the projectile and the longitudinal edges of the vanes may be tangent to the inner side faces of the frame itself. The table A is, of course, to be of such area as to permit of the 25 complete rotation of the projectile when the frame is moved, as set forth.

I claim:

1. In combination with an object of circular cross section to be gaged, a horizontal 30 plane-table for supporting said object, a rectangular frame inclosing and tangent to opposite sides of the circumferential periphery of said object and means for supporting said frame in a horizontal plane passing 35 through the axis of the circular object, said

frame being movable transversely over said table to cause rotation of said object within said frame.

2. The combination of claim 1, further including detachable plates within said frame and tangent to said opposite sides of the circumferential periphery of said object. 40

3. In combination with an elongated cylindrical projectile, a horizontal plane-table for supporting said projectile, a rectangular suspended frame inclosing and tangent to opposite sides of said projectile and means for supporting said frame in a horizontal plane passing through the axis of the circular object, said frame being movable 45 transversely over said table to cause rotation of said object within said frame. 50

4. In combination with an elongated cylindrical projectile, and guide vanes attached to one end thereof, a horizontal plane-table for supporting said projectile, a rectangular frame inclosing said projectile and said 55 guide vanes and tangent to opposite sides of said projectile and means for supporting said frame in a horizontal plane passing 60 through the axis of the circular object, said frame being movable transversely over said table to cause rotation of said object within said frame.

In testimony whereof I have affixed my 65 signature in presence of two witnesses.

GEORGE W. CHRISTIANS.
